UNITED STATES PATENT OFFICE.

FRANZ BURGER, OF FORT WAYNE, INDIANA, ASSIGNOR OF THREE-FOURTHS
TO HENRY M. WILLIAMS, OF SAME PLACE.

APPARATUS FOR CONVERTING HEAT INTO WORK.

SPECIFICATION forming part of Letters Patent No. 657,392, dated September 4, 1900.
Application filed August 4, 1898. Renewed January 8, 1900. Serial No. 780. (No model.)

To all whom it may concern:

Be it known that I, FRANZ BURGER, a citizen of the United States, residing at Fort Wayne, in the county of Allen and State of Indiana, have invented certain new and useful Improvements in Apparatus for Converting Heat into Work, of which the following is a specification.

The object of my invention is to avoid the loss of power resulting from the ordinary methods of utilizing the heat energy of fuel in that class of gas-engines in which combustible gas and vapor or air are mixed together and introduced into and exploded in a cylinder, and to also avoid the consumption of energy requisite in other classes of gas-engines to subject air to an excessive pressure, as well as to avoid the difficulties incident to operating valves under a high pressure.

To this end my invention consists in first compressing the air to a pressure of about one hundred (100) pounds, more or less, which is much less than what I mean by "excessive pressure," which is sometimes as high as five hundred (500) pounds—as, for instance, in the "Diesel" engine. The compressed air is stored in a reservoir, and the pressure should be maintained therein substantially uniform with the working pressure desired in the cylinder. Air from the reservoir is introduced alone into the cylinder at the beginning of the forward stroke, and when the piston has moved a predetermined distance fuel in either liquid or gaseous form is injected into the cylinder through a separate passage in close proximity to the air-passage, and a portion of the incoming air is mixed with the fuel and the mixture ignited within the cylinder. The remainder of the incoming air mixes with and causes the burning fuel to follow up the moving piston, and thus every particle of carbon is consumed and converted into work, thereby preventing any waste of fuel and producing a non-visible odorless exhaust. When the piston has moved a predetermined distance, the supply of fuel is cut off, and subsequently the supply of air, before the piston has completed its outward stroke. By this means I avoid the loss of energy from highly compressing the air. There is no dif-

ficulty in manipulating the valves, while I am enabled to maintain the pressure against the piston for a much greater proportion of the stroke with a much less consumption of fuel than has heretofore been practicable.

In carrying out my invention I may make use of various different apparatus and details of apparatus and will now describe one which has proved to be effective, reference being had to the accompanying drawings, in which—

Figure 1 is a plan in part section of a gas-engine constructed to utilize my improved mode of converting heat energy or fuel into work. Fig. 2 is a longitudinal sectional elevation. Fig. 3 is a reverse side view of the cylinder and adjuncts. Fig. 4 is a section on the line 4-4, Fig. 3. Fig. 5 is a detail view looking in the direction of the arrow, Fig. 4. Figs. 6 and 7 are detached detail views. Figs. 70 to 7 are on a larger scale than the other figures. Fig. 8 is an enlarged longitudinal sectional view of the engine-cylinder and the valve mechanism connected thereto.

In carrying out my invention I make use of a cylinder 1 of any suitable construction containing a piston 2, connected by the piston and connecting rods 3 5 with the crank 6 on the shaft 11, or the piston may be connected in any other suitable way with means for converting its movement into motion of the desired character, and I also make use of a reservoir 14, in which air is stored under compression, preferably by the action of the piston 2 on its forward motion, as hereinafter described. Air from the reservoir 14 is introduced alone into the rear of the cylinder at the pressure in the reservoir—say one hundred pounds—during the first part of the piston's outward movement. After the piston 90 has moved outward to a certain extent gas is introduced also into the rear end of the cylinder adjacent to the point where air is flowing in, and at this point there is arranged a suitable heating means whereby the inflowing 95 air and the gas are heated, and there is also arranged an igniter, whereby the inflowing air and gas are together burned. By this means the combustibles will burn in the cylinder with a clear blue flame without the deposit of carbon, the necessary air for supporting the combustion of fuel being supplied by the in-

flow without necessarily drawing upon that already in the cylinder, and as the piston moves forward the burned products of combustion are carried forward with it and impart their heat to the air at the rear of the piston, causing the continued expansion of the latter, while the burned products of combustion are carried away from the flame, so as not to interfere with the combustion. As a result, every particle of carbon is consumed, the heat energy of the fuel is converted into work, a greater range of expansion is obtained than when the charge is exploded at once, while the expansion prevents an undue increase in temperature.

While different means may be employed for heating the air and gas as they pass into the cylinder, I prefer to make use of what I term a "regenerator" 31—that is, a mass of any material which will retain heat imparted to the same—shown as a wire screen, which is arranged within the valve-casing *a* between the air-inlet valve 18 and the port *y* in the center of the rear head of the piston.

25 In front of the regenerator 31 is a plate 32, which is perforated only near the periphery, so that the air as it enters the cylinder is drawn toward the walls thereof.

The fuel-injector consists of a tube 33, which 30 extends into the cylinder 1 in close proximity to the perforated plate 32. Within the tube 33 is a nozzle 34 and a plate 35 in front of the nozzle, which nozzle and plate have coinciding perforations, and in the sides of the tube 33 between the nozzle and the plate 35 and beyond the latter are perforations 36, so that when the gas is injected through the nozzle and through the perforations toward the end of the tube 33 the fresh air will be drawn into 40 the tube through the perforations 36, the presence of fresh air at this point being insured by the arrangement of the plate 32 with its perforations near the periphery.

As there must be a space for the combustion of the mixed gases, but as it is desirable to limit this space, I place near the end of the pipe 33 a mass of broken-up or granular material 41, which is preferably capable of retaining the heat imparted to it by the combustion of the gases. For instance, the material may be wire screen or broken fire-brick, &c. This not only affords a space for the combustion of the gases, but serves to prevent them from passing too freely into the body of the cylinder, and the heat of the material tends to greatly increase the heat of the fuel and facilitate the combustion with increased economical results, and, further, after the engine has been running for a short 55 time the said material serves practically as an igniter.

In order to ignite the gases in the first instance, I provide a special igniter 40, which, as shown, is a coil of platina wire intervening between terminals 37 39 in circuit with any suitable source of electricity, which circuit, however, may be broken after the ma-

terial 41 has become incandescent or heated to the desired extent. As the air is introduced in the first instance from the reservoir 14 under a pressure of about one hundred pounds, this is sufficient to start the engine without the use of the ordinary starting appliances, which are often the occasion of expense and difficulty in connection with gas engines of high power. In the construction shown I charge the reservoir 14 by means of the piston 2, air passing into the forward end of the cylinder through a channel 9, provided with a spring-seated valve 10 and passing out through a casing 7, containing a valve 12, which lifts under the outflow of the air, the latter passing from the casing 7 through a pipe 13, having a branch communicating with the reservoir 14 and another branch, provided with a hand-valve 15, communicating with the casing *a* through a port 17 below the valve 18.

The gaseous fuel is forced into the injector-pipe 33 by means of any suitable forcing apparatus—as, for instance, a pump *P*—the plunger 46 of which is operated from an eccentric on the shaft 11, so constructed as to avoid the use of a gas-compressing chamber, the plunger 46 being forced outward to compress the gas as the piston 2 moves forward, and I have so constructed the pump that this may be done without any material diminution in the pressure of the gas. Thus the pump-cylinder 42 has at its head a suction-valve 48, closing the port communicating with the fuel-supply pipe 49, the valve seating under the pressure of a spring, so as to rise when the plunger 46 moves outward. On the return movement of the plunger the valve 48 seats and a check-valve 50, closing a channel 51 in the head 47 of the piston, rises, permitting the gas to pass into the contracted space 52 back of the said head and around the plunger, in which space it is compressed to the desired extent as the plunger moves outward.

As a means of controlling the engine I provide for cutting off the fuel-supply when the speed becomes too great, as by means of a valve 43 in the channel between the pump and the pipe 33, which valve is controlled in any suitable manner by means of a governor. One governor construction is illustrated in the drawings and will now be described.

To the eccentric-rod 45 is pivoted at 53 a tappet-arm *N*, provided with tappets *O O'*, between which extends a wrist-pin *p* upon a crank-arm *H* of a stationary stud *L*. On one side of the arm *H* is a pawl *j*, which engages with a cam plate or disk *B*, fastened to the sleeve *T*, rocking on the stud *L*, carrying a cam *d*. A pin *R* projects from the cam-plate *B* and serves as a stop for the arm *H*, as shown in Fig. 7. In front of the cam-plate *B* and loose on the stud *L* turns a loose eccentric *C*, and over the edge of this eccentric extends the end of the pawl *j*. To the eccentric *C* is pivoted the governing-rod 54, extending to

the governor 55, the movement of which turns the eccentric to different positions. When the arm H is pushed by the tappets O O' from one side to the other, the pawl j will engage 5 the shoulder of the cam-plate B and turn the latter to the left, turning with it the cam d, which acts upon the roller 56 on a rod 57 on the valve 43, thereby opening the latter. As the pawl j travels farther to the left its contact 10 with the edge of the eccentric C lifts it away from the shoulder of the cam-plate B, liberating the latter, which is then forced to the right by means of a weight or spring—as, for instance, a spring S—acting upon the end 15 of a rod D, pivoted to the cam-plate, as shown in Fig. 3. To prevent too sudden a movement, the end of the rod D carries a piston 70, which acts as a dash-pot in a casing 71. It will be seen that in proportion as the eccentric C 20 is set to different positions by the change in the position of the governor 55 the pawl j will be lifted at different points, thereby varying the cut-off.

If the valve 43 was closed before the plunger reached the end of its stroke, the gas might 25 be too highly compressed, and I therefore provide a return-pipe 60, communicating with the cylinder and with the supply-pipe 49 and place in this return-pipe a self-acting valve 30 48^a, compressed by an adjustable spring 59 and which will lift under excessive pressure, according to the adjustment of the spring, and permit the gas to pass back to the supply-pipe.

The spent gases are discharged by the return 35 movement of the piston 2, being forced through the perforations of the plate 32, through the casing a, and out through an exhaust-port x, controlled by a valve 61. As the spent gases in their discharge pass in contact 40 with the regenerating materials 41 and 31 the latter receive the heat of the gases, which is thereby utilized for heating the incoming air and fuel and for maintaining the material 41 in an incandescent condition, so as to dispense 45 with the necessity of an additional constant igniter.

The exhaust-valve 61 is normally maintained in its seat by a spring 73 and is lifted by a cam 65 on the shaft 11, which cam acts 50 upon a pivoted arm 64, connected by a rod 63, extending to a bell-crank lever 62, one arm of which projects beneath the stem of the valve 61.

The admission of air from the pipe 13 to 55 the cylinder 1 is controlled by the cam 65 on the shaft 11, which cam acts upon an arm 20, connected by a spring 74 with the arm 64 and also connected by a connecting-rod 22 with a lever 23, from which a rod 24 extends to 60 an arm 25 upon a rock-shaft 26, which passes into the valve-casing a. An arm 27 upon the shaft 26 bears upon the stud 28 upon the side of the stem of the valve 18, and when the shaft 26 is rocked it depresses the 65 said valve and permits the compressed air to pass to the cylinder.

The parts are so adjusted that the valve

18 will be opened when the crank 6 is upon its dead-center.

Without limiting myself to the precise construction and arrangement of parts shown, I claim as my invention—

1. In an apparatus for utilizing the heat energy of fuel, the combination of a cylinder and piston, means for supplying the cylinder 75 with compressed air alone during the first portion of the forward movement of the piston, means for thereafter injecting a fuel into the cylinder concurrently with the air and mixing it with a portion of the incoming 80 air, means for heating the incoming air and fuel, and means for igniting the mixture, substantially as set forth.

2. The combination with a cylinder and piston of a gas-engine, of means for supplying compressed air alone to the cylinder during the first portion of the forward movement of the piston, means for thereafter injecting a fuel into the cylinder concurrently with the air and mixing it with a portion of the 90 incoming air, means for heating the incoming air and fuel, means for igniting the mixture, means for cutting off the supply of fuel at a predetermined point of the stroke of the piston and means for subsequently cutting 95 off the supply of air, substantially as set forth.

3. The combination with the cylinder and piston of a gas-engine, of a regenerator arranged between the cylinder and the exhaust-port, means for passing compressed air 100 through the regenerator into the cylinder, means for injecting fuel under pressure into the cylinder and mixing it with a portion of the incoming air before its entrance into the cylinder, and an igniter against which the 105 mixture is discharged, substantially as set forth.

4. The combination with the cylinder and piston of a gas-engine, of a casing on the cylinder containing an inlet-port provided with 110 a valve and communicating with a reservoir of compressed air and with the cylinder, and also provided with an exhaust port and valve, a regenerator between the exhaust-port and cylinder through which the compressed air 115 passes to the cylinder, means for injecting fuel under pressure into the cylinder and mixing it with a portion of the incoming air before its entrance into the cylinder, and an igniter against which the mixture is discharged, substantially as set forth.

5. The combination with the cylinder and piston of a gas-engine, of a valved inlet-port communicating with a reservoir of compressed air and the cylinder, a disk supported 125 in the cylinder in front of the inlet-port and having a solid central portion and outer perforated portion concentric therewith, and a fuel-injector supported within the cylinder in close proximity to the disk and receiving 130 the air flowing through some of the perforations in the disk, substantially as and for the purpose set forth.

6. The combination with the cylinder and

piston of a gas-engine, of a casing on the cylinder containing an inlet-port provided with a valve and communicating with a reservoir of compressed air and with the cylinder and provided also with a valved exhaust-port, a regenerator between the exhaust-port and cylinder through which the compressed air passes to the cylinder, a disk supported, in the cylinder adjacent to the inlet-port, said disk having a solid central portion opposite the inlet-port and a concentric perforated outer portion, an igniter within the cylinder in close proximity to the solid portion of the disk, and a fuel-injector discharging onto the igniter, substantially as described.

7. In a gas-engine, the combination with the cylinder and piston, of means to introduce compressed air to the cylinder, a disk

supported in the cylinder and having a solid central portion and a concentric perforated portion through which latter the air passes to the cylinder, a fuel-injector in close proximity to the said disk having openings registering with openings in the disk, means to supply fuel to the injector, a valve 43 in the fuel-supply passage, and a governor on the casing to control the movement of the valve, substantially as and for the purpose specified.

In testimony whereof I have signed my name to this specification in the presence of two subscribing witnesses:

FRANZ BURGER.
